APPARATUS FOR REFINING FIBEROUS MATERIALS

Henri Léon Xavier Vincent, Malines, Belgium

Application October 20, 1947, Serial No. 780,774
In Great Britain February 16, 1939

1 Claim. (Cl. 92—26)

1

This invention relates to apparatus for the treatment of fibrous materials and the present application is a continuation-in-part of application, Serial No. 310,905, filed December 26, 1939, now abandoned.

It is an object of the present invention to provide improved apparatus for the preliminary treatment of fibrous material such as the pulp used in the paper industry, so as to obtain from such treated pulp a paper of better quality, and which at the same time shall be economical in operation.

It has previously been proposed for refining fibrous substances to load the pulp in a thick state into apparatus having an outer rotating drum. Rotating rollers are strongly urged against each other and between which rollers the pulp is repeatedly thrown by the outer drum in such a manner as to be instantly and violently dried and dishevelled by the water driven through the pulp by the rollers. One of the rollers rests in fixed bearings and is maintained in rapid rotation by a motor through suitable gearing. The other roller is also driven by suitable transmission means and is urged against the first roller by means of a screw-threaded rod and spring.

It has also been proposed in a beating or refining machine for preparing stock for paper and the like to use a rotating drum with a number of rollers therein, which may be ribbed, toothed or fitted with rivets or the like. Such rollers when the drum is rotated are caused by friction with it and with each other to rotate, substantially maintaining their spatial relation to the axis of the drum and to each other by virtue solely of the friction with each other and with the drum resulting from their weight. In such apparatus the material is crushed by the rolling and rubbing action of one roller upon the other and upon the drum.

It has also been proposed in hydrators for paper stock or pulp to use a casing the inner wall of which is provided with gears which intermesh with other inner planetary gears, the teeth of the gears being of the spur type, or helical so as to subject the pulp to a high pressure.

The present invention pertains to improved apparatus for the treatment of fibrous materials, more particularly of the pulp used in the paper industry. The apparatus comprises a moving supporting and refining surface for the fibrous material and a plurality of rotating rollers. The surface of the rollers are provided with grooves or the like or grooves which in the direction of

2

their length are substantially perpendicular to the axis of rotation of the rollers. The rollers are positively held at a fixed distance from each other and the moving surface bringing the fibrous material successively between it and each of the rollers.

One at least of the surfaces between which the pulp is pressed may be rendered rough. For instance, the outer surface of the projecting parts or ribs between the grooves of the rollers and/or the surface of the inner wall of the outer cylinder may be rendered rough, or by covering them with materials of suitable nature, for instance wood, lava, basalt, synthetic substances.

15 The accompanying drawing illustrates diagrammatically and by way of example one mode of carrying out the invention.

In the drawing:
Fig. 1 is a longitudinal section of apparatus exhibiting the invention,

Fig. 2 is a side view, and

Fig. 3 shows an elevation of a detail on a larger scale.

Referring to the drawing, 1 is a frame which 25 may be made of structural iron or of cast pieces. The frame 1 carries a transmission system including a motor 2 which actuates an outer cylinder 3 by a belt trained about a track 15, but which may also be made to actuate the central shaft 4 of the cylinder 3. A gear mechanism 18, 19 may be used to control the speed of inner rollers 11, for instance so as to exert a braking action upon these rollers relatively to the speed which would be imparted to them by the rotation of the outer cylinder 3, through the intermediary of the pulp.

The cylinder 3 is provided with annular tracks 6 against which rest rollers 14 (Fig. 2) secured to shafts rotating in bearings mounted on the frame 1. The cylinder 3, which may be made of metal 40 or metal alloy, may be caused to rotate by any suitable transmission means.

The rollers 11 are provided with circumferential grooves 20 (Fig. 3). This is an essential feature of the present invention as the grooves thus provided upon one of the rotating surfaces, greatly improve the final product. The grooves are circumferential. The rollers 11 which may be made of metal or metal alloy, are loosely mounted upon their supports 12, the rotation of the rollers 11 being ensured by the rotation of the outer cylinder 3, and if necessary by the transmission 18, 19. The rollers 11 are provided along their entire length with equally spaced circumferentially projecting ribs 21 all of equal height with intermediate 50 grooves 20 all of equal depth, the outer surface

of the projecting ribs being cylindrical and the grooves in the direction of their length being substantially perpendicular to the axis of rotation of the rollers.

The outer surface 21 (Fig. 3) of the projecting parts or ribs between the grooves 11 may be rendered rough by being serrated for the purpose of preventing slipping of the pulp when seized by the ribs. The grooves 20 are approximately three times wider than the ribs 21. These grooves 20 and annular ribs are arranged throughout the active length of the rollers 11. This spacing of the ribs 21 provides relatively wide grooves 20 therebetween which have been found to produce an unusual fine type of pulp. This result is possibly due to the fact that the widely spaced ribs allows the accumulation of material quantities of the treated material in the grooves 20.

The number of rollers inside the outer cylinder may of course be varied. In the drawing, twenty-six rollers are shown. In certain cases however a different number or smaller number of rollers may be used. These rollers may be held in circumferential spaced relation from each other by arms 12 radiating like the spokes of a wheel from a central shaft. Each arm is provided with resilient means for the respective roller and with its own lifting device for varying the pressure of the roller upon the pulp. If desired other known means may be used for resilient adjustment of the rollers, the essential feature common to all these means being that the rollers are positively held at fixed distance from each other.

In the drawing, one roller is shown as being supported by arms 12 secured on the central shaft 4 and provided with an adjustment device 13 for varying the pressure of the roller upon the pulp. A similar arrangement may be employed for all the rollers.

Any known feeding means may be used for introducing the pulp into the apparatus. The removal of the treated pulp is preferably effected on the end side opposite to that of the feeding. Any known means may be provided for facilitating the emptying of the cylinder 3 and for bringing the cylinder 3 to the emptying position.

It is to be understood that the above description is given only by way of example. The shape,

size, materials used and all modifications of details may be made without departing from the scope of the invention as defined by the claim. The invention may be usefully applied to fibrous material such as asbestos for mixing with other materials, such as water, cement, and the like. The invention may also be used for refining other cellulosic materials, for instance sawdust, cotton, rags, and the like.

10 I claim:

Apparatus for the treatment without tearing of pulp fibers comprising, a cylinder rotatable about its axis and having a smooth cylindrical inner surface, a plurality of rollers mounted within the cylinder for rotation and provided along their entire active lengths with a plurality of circumferentially extending equally spaced grooves all of which are of equal depth, projecting ribs on said rollers intermediate the grooves, the outer surface of said projecting ribs being of equal height and being arranged substantially perpendicular to the axis of said rollers, serrations carried by the peripheral portions of said ribs, and the width of said grooves measured axially of the rollers being approximately three times the width of the projecting ribs, and means for holding the rollers at a fixed distance from each other adjacent the inner surface of the cylinder.
